SHOELACE TIGHTENER

Thomas C. Cairns, Niles, Ohio

Application April 20, 1950, Serial No. 157,097

3 Claims. (Cl. 24—140)

1

This invention relates generally to shoes and more particularly to a device attachable to shoes and more particularly to a device attachable to a shoe to enable the shoelace thereof to be tightened without tying the same.

The principal object of the invention is the provision of a shoelace tightener that may be applied to a shoe to manipulate the shoelace thereof.

A further object of the invention is the provision of a shoelace tightener that may be applied to children's shoes and the laces thereof tied and engaged in the device so that they may be tightened and loosened thereby.

A still further object of the invention is the provision of a shoelace tightener of simple and economic design capable of inexpensive manufacture.

A still further object of the invention is the provision of a shoelace tightener that may be readily applied to conventional laced shoes and usable therewith for the indicated purpose.

The shoelace tightener shown and described herein has been designed to facilitate the fastening of children's shoes, it being well known that children are incapable of tying shoelaces in a satisfactory manner for several years. By using the device disclosed herein, one of which is applied to each of the child's shoes, the shoelace may be pre-tied loosely in the shoe arranged in position in the device so that the child need only rotate the exposed portion of the device to either tighten or loosen the shoelace, as desired.

Means is formed in the device for holding the same in any desired position and the device thus operates satisfactorily to hold the child's shoes in laced or unlaced position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a perspective view of a shoe showing the shoelace tightener installed thereon.

Figure 2 is an enlarged transverse section through a portion of a shoe showing the shoelace tightener in position therein.

Figure 3 is a top plan view taken on line 3—3 of Figure 2.

2

Figure 4 is a vertical section on line 4—4 of Figure 2.

Figure 5 is a horizontal section on line 5—5 of Figure 4.

By referring to the drawings and Figure 3 in particular it will be seen that a child's shoe has been illustrated and includes a heel 10, sole 11, toe portion 12 and oppositely disposed upper portions 13 and 14. The upper portions 13 and 14 are positioned in oppositely disposed spaced relation partially overlapping the tongue 15 of the shoe. The oppositely disposed edges of the uppers 13 and 14 are provided with a plurality of eyelets 16 and 17, respectively. The eyelets 16 and 17 receive a shoelace 18 threaded therethrough and back and forth through the eyelets 16 in the upper 13 and the eyelets 17 in the upper 14. The shoelace 18 is preferably positioned through the eyelets so that the oppositely disposed pair of eyelets positioned next to the top pair are not engaged by the shoelace 18, it being understood that the shoelace 18 is loosely positioned and tied so that the child may put on and take off the shoe with the lace in loose position.

25 The shoelace tightener is affixed to the shoe by locating a transverse flexible band 19 between the tongue 15 and the uppers 13 and 14, as best shown in Figures 2 and 3 of the drawings, the transverse flexible band 19 being formed of thin, deformed metal or plastic material, as desired, and capable of readily adapting itself to the arcuate contour of the uppers 13 and 14 of the shoe. Longitudinally extending slots 20—20 are positioned in the band 19 and in spaced relation with 30 respect to one another and fasteners such as rivets 21—21 are positioned loosely in the slots 20—20 and engaged in the pair of oppositely disposed eyelets 16 and 17 next to the uppermost pair of said eyelets, as best shown in Figure 1 of the drawings. In such position the fasteners such as rivets are secured so that the band 19 is loosely affixed to the uppers 13 and 14 and so that the same may be moved toward or away from one another in the usual manner with the fasteners 35 or rivets 21 sliding in the slots 20.

The band 19 has an opening 22 midway between the slots 20—20 and which opening 22 serves to mount a rotatable knob 23 thereon as by means of a fastener 24. The rotatable knob 50 23 has a deep transverse slot 25 therein and a central circular area 26 provides clearance for the head of the fastener 24 which serves as a means securing the knob 23 to the band 19 while permitting it to rotate. The knob 23 has an opening 27 therein in which a spring 28 is caged so as to urge a ball 29 outwardly and against

a radially spaced pattern of depressions 30 formed in the band 19. Thus, the knob 23 will remain in predetermined position by reason of the engagement of the ball 29 with one of the depressions 30. The laces 18 are engaged in the deep transverse slot 25 of the knob 23, as best shown in Figures 1 and 3 of the drawings, so that rotation of the knob 23 will wind the laces 18 about the narrow portion of the knob 23 and thereby tighten the same with respect to the uppers 13 and 14 and thus pull the same together. When they have thus been suitably moved toward one another to hold the shoe on the child's foot, the ball 29 registering in one of the depressions 30, will hold the knob 23 and the laces 18 in tightened position. The child can then manipulate the laces by merely turning the knob 23 from one side to the other.

It will occur to those skilled in the art that the laces 18 may be positioned through the eyelets 16 and 17 in several different arrangements so that sections of the laces may be engaged in the knob 23 and the laces tightened by rotating the knob.

It will thus be seen that a simple and efficient device has been disclosed which may be attached to a child's shoe including the usual eyelets and laces and used to tighten or loosen the laces so as to affix the shoe to the child's foot or permit it to be removed therefrom. The device is capable of economic manufacture and may be easily installed on the shoe by positioning the transverse band 19 over the tongue and under the uppers of the shoe and the fasteners engaged in the slots in the band and in oppositely disposed pairs of eyelets in the shoe. It will be seen that by removing the fasteners 21 the device may be removed from the shoe and installed in another shoe if desired.

It will thus be seen that the device disclosed herein meets the several objects of the invention.

Having thus described my invention, what I claim is:

1. A shoelace tightener for a shoe having a tongue, oppositely disposed uppers overlying the tongue and eyelets positioned in the edges of said uppers and comprising an arcuate body member adapted to be disposed transversely beneath the said uppers and over said tongue, longitudinally extending slots in the said body member and fasteners positioned in oppositely disposed relation in the said eyelets in the uppers and slidably engaged in the said slots in the said body member whereby the body member is loosely secured to the said uppers, a knob pivotally affixed to said body member midway between the ends thereof and located between the

edges of the said uppers, and a deep transverse slot formed in said knob.

2. A shoelace tightener for a shoe having a tongue and oppositely disposed uppers overlying the tongue and eyelets positioned in the edges of the said uppers, said tightener comprising an arcuate body member adapted to be disposed transversely beneath said uppers and over said tongue, spaced longitudinally extending slots in the said body member and fasteners positioned in oppositely disposed relation in the said eyelets in the uppers and slidably engaged in the said slots in the said body member whereby the body member is loosely secured to the said uppers, a knob pivotally affixed to said body member midway between the ends of the slots therein and positioned between the edges of the said uppers, a deep transverse slot formed in said knob, and friction means in said knob engaging said body member for holding the said knob in predetermined position.

3. A shoelace tightener for a shoe having a tongue and oppositely disposed uppers overlying the tongue and eyelets positioned in the edges of the said uppers, said tightener comprising an elongated arcuate body member adapted to be disposed transversely beneath the said uppers and over said tongue, spaced longitudinally extending slots in the said body member and fasteners positioned in oppositely disposed relation in the said eyelets in the uppers and slidably engaged in the said slots in the said body member whereby the body member is loosely secured to the said uppers, a knob comprising a stem and an enlarged head portion rotatably affixed to the said body member midway between the ends thereof and positioned between the edges of the said uppers, and a deep transverse slot formed in the head and stem of the said knob.

THOMAS C. CAIRNS.
